UNITED STATES PATENT OFFICE.

CHARLES BROWN, OF CHICAGO, ILLINOIS.

FIRE-EXTINGUISHING DEVICE.

SPECIFICATION forming part of Letters Patent No. 752,327, dated February 16, 1904.

Application filed July 24, 1901. Serial No. 69,591. (No model.)

To all whom it may concern:

Be it known that I, CHARLES BROWN, a citizen of the United States, and a resident of Chicago, in the county of Cook and State of Illinois, have invented certain new and useful Improvements in Fire-Extinguishing Devices; and I do hereby declare that the following is a full, clear, and exact description thereof, reference being had to the accompanying drawings, and to the letters of reference marked thereon, which form a part of this specification.

This invention relates more particularly to a fire-extinguishing device to be established in a building of any desired construction and of any number of stories.

Heretofore a water-service pipe extending to the top of the building has been provided with hose connections for each floor. It frequently happens, however, that fire occurs on different floors of a building at the same time, thereby necessitating the use of water from said pipe on several floors at the same time. When this occurs under the system heretofore used, the opening of the pipe at the lower or intermediate floors acts to reduce the pressure at the upper floor or floors, thereby seriously decreasing, if not entirely destroying, the efficiency of the service.

The object of this invention is to provide an absolutely reliable and efficient means for extinguishing fires on whatsoever floor or floors they may occur, said means to be at all times under the control of an operator or engineer within the building and affording ready access from the exterior to enable ready connection to be made by the city fire service.

The invention embraces many novel features; and it consists of the matters hereinabove described, and more fully pointed out and defined in the appended claims.

In the drawings, Figure 1 is a vertical section through a building provided with a device embodying my invention. Fig. 2 is an enlarged horizontal section taken on line 2-2 of Fig. 1. Fig. 3 is a front view of the outer annunciator and hose connections. Fig. 4 is an enlarged vertical section through one of the compartments, showing the hose in position upon its support. Fig. 4^a is a side elevation

of the hose-coils. Fig. 5 is a side elevation of one of the hose-supporting hooks. Fig. 6 is a front elevation of the same. Fig. 7 illustrates a device for automatically opening the door of a hose-closet and setting a signal. Fig. 8 is a sectional view of another form of my invention, showing a stand-pipe of large size constructed within the building and extending through the floors. Fig. 9 is a diagrammatic view, partly in section, of the automatic door-opener, light, and thermostat.

In the drawings, A indicates the outer wall of the building; B, the basement-floor; B' B² B³, &c., the succeeding floors above the same. B⁴ indicates the roof. Said building may be of any desired construction. Extending from said basement-floor upwardly for the entire height is a fireproof casing, herein shown as cylindric, and which may, if preferred, be constructed of sheet metal or other desired material, and which, as shown, provides a separate compartment on each floor.

C indicates a main leading from a pumping plant or station, herein shown as located within the building and preferably under the control of an engineer located in the basement, but which may, if preferred, be located without the building. Said main, as shown in Fig. 2, extends to a point adjacent to the lower end of said casing and is there connected with laterally-extending branches C' C', which extend partly around the casing, and is also provided with a valve C², adapted to regulate the water-supply to said branches. From said branches valved pipes (indicated by c' c² c³, &c.) extend upwardly within said casing and terminate one above each of said floors in a fitting adapted to afford connection with one or more hose D, a sufficient length of which is provided at each floor within said casing to extend to any desired point on said floor. As shown, two leads of hose are connected, one on each side of the service-pipe, and supported, as before described, on each side of said compartment. Any desired means for coiling, supporting, or storing said hose within the compartment may be used. As shown, however, and preferably, the hose is supported,

as shown in Figs. 4 and 4^a, on a plurality of hooks located near the top and bottom of said

compartment and coiled successively around upper and lower hooks. Said hooks are preferably spring-controlled and comprise bell-crank levers d , pivoted on lugs d' on an inner 5 transverse wall of said compartment. One arm of each bell-crank d extends outwardly in position to support the fold or loop of a hose. The other arm extends vertically and is engaged by a spring d'' of sufficient tension 10 to normally support the weight of the hose and to hold said bell-crank lever in its supporting position. A slight pull on the hose, however, is sufficient to pull the supporting ends of said levers downwardly against the 15 tension of the spring, thereby permitting the coils of hose to be released therefrom. Ladders E , as shown, are provided on the interior of each compartment on each floor, secured on the side walls of the casing to facilitate the 20 hanging, suspending, or coiling of said hose-sections, as before described. Each of said compartments is provided with a door provided with an electrical door-opener of any desired construction, as herein shown. However, 25 for convenience of illustration said opener comprises an electromagnet H , the armature h of which is provided with an elongated and laterally-turned arm h' , which is pivoted to the wall of the casing H' . Said 30 arm h' contacts with one arm of a pivoted lever I , on the other arm of which is carried the latch i , adapted to be normally held in engagement in a suitable catch in the door-jamb by means of a spring i' .

35 At convenient points about the building and above each floor thermostatic fire-alarms J are secured, which may also be of any desired or familiar type and are electrically connected with the door-opening device of the compartment on that floor and with an annunciator F , indicating the various floors and located in the basement convenient of access to the engineer or other operator. An electric light or lights K may be provided in each compartment, also 40 in the same circuit with the opener, annunciator, and thermostat, in such manner that when the temperature in the room rises sufficiently to actuate the thermostat the door automatically opens, the light is turned on, and the 45 annunciator indicates the floor where water is desired. For the purpose of enabling connections to be made with said interior pipes from without the building pipes G extend through the side walls and connect, respectively, therewith. Pipes $G' G'' G'''$, &c., 50 extend upwardly along or adjacent to the wall and are provided with inner hose connections, so that, if preferred, water may be directed therefrom to any part of any floor. Each of 55 said pipes is provided with a hose connection on its outer end, which extends through the wall, and an annunciator F' , corresponding with the annunciator F , and which is also connected in the circuit before described, is located adjacent to said outer ends and acts to

indicate to an observer without the building the location of the fire, thereby enabling the connection to be made with the desired pipe.

The operation of my device is as follows: The pipes $c c' c''$, &c., may preferably at all 70 times be filled with water under a desired pressure from pumps of any desired kind under the control of the engineer in the basement. Upon the temperature rising in any part of the building sufficient to actuate the 75 thermostats J the alarm is sounded in the engine-room, and both annunciators indicate the floor where water is needed, and the door of the compartment on the said floor is opened automatically and the lights turned on. A slight 80 pull on the hose releases the same from its supports, and the same may be dragged to the point where the water is to be delivered. Should it be desirable, the valves in all of 85 said pipes except that leading to the desired floor may be closed, thus diverting the full pressure to that floor. Obviously, if preferred, all of said valves may ordinarily be closed when the system is not in use, in which case it will only be necessary for the engineer 90 to open the valve for the pipe indicated on the annunciator when the alarm is given. Should the alarm occur at night when no engineer is in attendance, the city fire department may 95 connect with the indicated pipe on said wall-annunciator and direct water to the desired floor, as before described. Obviously it is not essential that a casing, as described, continue for the entire height of the building. Instead separate compartments may be provided 100 on each floor, as indicated in Fig. 1, and the same may be in vertical alinement or otherwise, as preferred. Obviously, if preferred, also, a continuous stand-pipe may be provided within a building or adjacent thereto and hose 105 connections provided for each floor, as shown in Fig. 8, and an annunciator provided in the engine-room and also in the side wall to indicate the point where the pressure is to be utilized. In this construction pipes $G G'$, &c., 110 lead from said side-wall annunciator both to said stand-pipe and to hose connections on each floor, thereby permitting a fire-engine without the building to be utilized in maintaining the pressure in the stand-pipe or permitting the hose connections at the side wall 115 to be utilized, as before described.

Obviously many details of construction may be modified without departing from the principle of my invention.

I claim as my invention—

1. A plurality of service-pipes adapted to permit fluid to be conducted therethrough and terminating respectively one on each floor of a building or the like, a fireproof compartment on each floor of the building adapted to contain said end of a pipe and leads of hose connected with said end and adapted to convey the fluid to a desired point.

2. In a device of the class described, a fire-

proof compartment located on each floor of a building, and adapted to contain the upper end of a fluid-conducting pipe, the other end of which communicates with a source of fluid-pressure, a lead of hose connected with said pipe within said compartment and supported on a wall thereof, thermostats located about the building on each floor, an annunciator connected therewith designed to indicate the location of a fire or the like and means operated from the thermostat acting to open a door in the compartment to permit access to the hose.

3. In a device of the class described, the combination with a main service-pipe of valved pipes connected therein and terminating one above each floor of a building, a fireproof casting surrounding each of said delivery ends of pipe, leads of hose therein connected with said pipes and means in the engine-room for automatically indicating the location of a fire for opening the door of the compartment and illuminating said compartment.

4. In a building a plurality of valved service-pipes terminating one at each floor of the building, means under the control of the engineer for directing fluid through any or all of said pipes, a plurality of pipes extending inwardly from the side wall of the building and connected with the first-named pipes thereby permitting connection to be made from without the building and annunciators located in the outer wall and in the engine-room and acting automatically to indicate the pipe to be connected.

35 5. A building provided with a fireproof compartment on each floor, valved service-pipes, one of which terminates in a hose fitting in each compartment, a pressure-main with which said pipes are connected at their lower ends, a plurality of lengths of hose suspended in the compartment and connected in the hose-fitting, pipes extending through the outer wall of the building and communicating each with the service-pipes, other pipes extending through the wall and provided with independent hose-fittings within the building and automatic means for indicating the pipe in which pressure is desired both at the outer ends of said

outwardly-extending pipes and in the engine-room of the building.

6. In a device of the class described, a fireproof compartment designed to inclose the end of a service-pipe for water or the like, a plurality of supporting-hooks arranged transversely of the compartment near the top thereof and adapted to yieldingly support a plurality of folds or coils of hose connected with the service-pipe, a door for the compartment, and automatically-operated means for opening the door.

7. In a building, a fireproof compartment on each floor adapted to receive and inclose the end of a service-pipe, hose-fittings on said end adapted to permit a plurality of leads of hose to be secured thereon and a transverse partition in the compartment having adjustable spring-hooks secured thereon near the top thereof and adapted to support successive layers or folds of hose, a door in said compartment adapted to be normally locked and means operated by a thermostat for opening the door.

8. In a building, a metallic tubular casing extending through the floors thereof and provided at each floor with a grating separating the same into individual compartments for each floor, a plurality of service-pipes in said casing terminating one above each floor in a hose-fitting, a pump connected with the lower ends of said service-pipes, pipes extending through the outer wall of the building and having hose-fittings on their outer ends and connecting at their inner ends with said service-pipes, an annunciator adjacent to the pumps and one on the outer wall and means operated by a thermostat for indicating simultaneously on each of said annunciators the floor at which pressure is desirable.

In testimony whereof I have hereunto subscribed my name in the presence of two subscribing witnesses.

CHARLES BROWN.
